IMMERSION ROLL

Fred L. Still, Greenville, S. C.

Application May 12, 1934, Serial No. 725,368

4 Claims. (Cl. 28—28)

The present invention relates to new and useful improvements in immersion rolls for slashers used in the manufacture of textiles and has for one of its important objects to provide, in a manner as hereinafter set forth, a roll embodying a novel construction, combination and arrangement of parts through the medium of which better penetration of the yarn by the size will be had.

Another very important object of the invention is to provide an immersion roll embodying novel agitating means for eliminating substantially all lumps and unmixed compound, thus further aiding in the penetration of the yarn and assuring an improved product on the loom.

Other objects of the invention are to provide an immersion roll of the character described which will be comparatively simple in construction, strong, durable, highly efficient and reliable in use, compact and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:—

Figure 1 is a view in side elevation of an immersion roll constructed in accordance with the present invention.

Figure 2 is a view in vertical longitudinal section through the immersion roll.

Figure 3 is a view in vertical transverse section, taken substantially on the line 3—3 of Figure 2.

Figure 4 is a view in end elevation of the invention.

Figure 5 is a detail view in vertical longitudinal section, showing the connection of one end portion of one of the tubes to one of the headers.

Figure 6 is a detail view in vertical longitudinal section, showing the connection of one of the agitators to one of the spacers.

Referring now to the drawings in detail, it will be seen that the embodiment of the invention which has been illustrated comprises a pair of headers which are designated generally by the reference numeral 1, each header including a circular plate 2 having a plurality of tapered openings 3 therein. Extending between the headers 1 is a plurality of hollow tubes 4 of suitable metal having flared end portions 5 which are seated in the tapered openings 3. Hardwood pins 6 (see Figure 5) are provided in the end portions

of the tubes 4. The headers 1 further include countersunk disks 7 which cover and conceal the ends of the tubes 4.

The reference numeral 8 designates a plurality of spacers for the tubes 4, said spacers being substantially in the form of disks having peripherally spaced recesses 9 therein for the reception of said tubes 4. Agitators 10 of substantially S-shaped cross section (see Figure 3) are mounted between the spacers 8 and secured at their ends thereto, as at 11. The reference numeral 12 designates, in broken lines in Figure 3 of the drawings, the yarn traveling under the roll.

The outermost spacers 8 are fixed on the inner ends of trunnions 13 which extend centrally through the headers 1 and terminate in enlarged outer end portions 14 providing shoulders 15 with which said headers 1 are engaged. The trunnions 13 further include threaded portions 16 which receive nuts 17 which, in conjunction with the shoulders 15, secure said trunnions in the headers. Washers 18 are interposed between the nuts 17 and the headers 1.

It will thus be seen that an immersion roll has been provided wherein the construction is such that penetration of the yarn by the size will be materially aided. The spacers 8, in addition to supporting the agitator 10, support or brace the tubes 4 at intermediate points, as will be readily apparent. As the roll rotates in the usual manner the agitators 10 eliminate substantially all lumps and unmixed compound, another highly desirable feature.

It is believed that the many advantages of an immersion roll constructed in accordance with the present invention will be readily understood, and although a preferred embodiment of the invention is as illustrated and described, it is to be understood that changes in the details of construction and in the combination and arrangement of parts may be resorted to which will fall within the scope of the invention as claimed.

What is claimed is:—

1. An immersion roll of the class described comprising a pair of headers, spaced tubes extending between the headers, spacers mounted between the tubes at longitudinally spaced points, and agitators mounted between the spacers.
2. An immersion roll of the class described comprising a pair of headers, trunnions mounted centrally in said headers, spaced tubes extending between the headers, spacers mounted between the tubes at longitudinally spaced points, said spacers including disks having peripherally

2

spaced recesses therein for the reception of the tubes, and agitators mounted between the spacers.

3. An immersion roll of the class described comprising a pair of headers, each header including a disk having tapered openings therein, tubes extending between the headers and terminating in flared end portions engaged in the openings, fillers in the end portions of the tubes, 10 the headers further including disks countersunk in the first-named disks and concealing the ends

of the tubes, and trunnions mounted on the headers.

4. An immersion roll of the class described comprising a pair of trunnions, headers mounted, at an intermediate point, on said trunnions, tubes extending between said headers, a series of spacers mounted between the tubes, the outermost spacers being fixed on the inner end portions of the trunnions, and agitators extending between the spacers.
